[57] CLAIM

The ornamental design for shoe stitching, as shown and described.

DESCRIPTION

FIG. 1 is a perspective view of shoe stitching of my new design;

FIG. 2 is a right side elevational view of the shoe stitching of FIG. 1;

FIG. 3 is a left side elevational view of the shoe stitching of FIG. 1; and,

FIG. 4 is a rear elevational view of the shoe stitching of FIG. 1.

The broken line showing a shoe in FIGS. 1-4 is for illustrative purposes only and forms no part of the claimed design.
